(57) **CLAIM**

The ornamental design for a receptor and adapter assembly, as shown and described.

DESCRIPTION

FIG. 1 is an exploded view of a receptor and adapter assembly illustrating our new design;

FIG. 2 is a front perspective view of a receptor;

FIG. 3 is a side view thereof;

FIG. 4 is a top plan view thereof;

FIG. 5 is rear perspective view of an adapter; and,

FIG. 6 is a front view of a receptor.

In the drawings, the broken lines depict portions of a receptor and adapter assembly and form no part of the claimed design.
